TRACK LINE R

Filed Aug. 16, 1926

J.E.Varner INVENTOR.

BY

UNITED STATES PATENT OFFICE.

JOHN E. VARNER, OF ROCHELLE, ILLINOIS.

TRACK LINER.

Application filed August 16, 1926. Serial No. 129,621.

This invention relates to a track liner for use in connection with railway tracks, and has for its object to provide, in a manner as hereinafter set forth, a device of such class 5 for exerting a thrust either against the track rails of the track or the supporting means therefor to shift the track to the desired position.

A further object of the invention is to 10 provide, in a manner as hereinafter set forth, a track liner which may be easily set in position for effective operation, conveniently anchored in position with respect to the track, and which is adapted to operate equally well 15 with various size rails.

A further object of the invention is to provide, in a manner as hereinafter set forth, a track liner which is of relatively light 20 weight and which may be conveniently carried from point to point when desired.

Further objects of the invention are to provide, in a manner as hereinafter set forth, a track liner which is simple in its construction and arrangement, strong, durable, compact, portable, thoroughly efficient in its use, 25 conveniently set with respect to the track to be shifted for alinement, and inexpensive to manufacture.

With the foregoing and other objects in 30 view, the invention consists of the novel construction, combination and arrangement of parts as hereinafter more specifically described and illustrated in the accompanying drawings, wherein is shown an embodiment 35 of the invention, but it is to be understood that changes, variations and modifications can be resorted to which fall within the scope of the claims hereunto appended.

In the drawings wherein like reference 40 characters denote corresponding parts throughout the several views:

Figure 1 is a vertical sectional view of a track liner in accordance with this invention.

Figure 2 is a front elevation thereof.

Figure 3 is an inverted plan.

Figure 4 is a fragmentary view in top plan illustrating the thrust element.

Referring to the drawings in detail, a 50 track liner, in accordance with this invention comprises a base plate 1 of the desired length, width and thickness and which has the forward portion bifurcated to provide a pair of spaced arms 2, 3 for straddling a tie or sleeper. The forward edge of the base 1 is squared and the rear end has rounded cor-

ners as at 4. Formed integral with the lower face of the base 1, as well as depending therefrom is a pair of spaced anchoring lugs 5, 6 positioned in transverse alinement with respect to the base 1. The anchoring lugs are of tapered form. The lugs 5, 6 are positioned approximately at the transverse median of the lower face of the base 1. Formed integral with the lower face of the base 1, as 60 well as depending therefrom, is a tapered anchoring lug 7, of arcuate form and which intersects the longitudinal median of the lower face of the base 1. The lug 7 is positioned in proximity to the rear end of the 70 lower face of the base 1. The lower face of each of the arms 2, 3 incline upwardly from the rear end of an arm to the forward end thereof as indicated at 8, Figure 1.

Formed integral with the upper face of 75 the base 1, is a pair of upright supports 9 and each of which has its outer face flush with a side edge of the base 1. The supports 9 are of appropriate thickness, oppose each other and are arranged in spaced relation. The 80 lower part 10 of each support is of greater width than the upper part 11 thereof. The forward edge of the lower part 10 of each support is arranged in alinement with the rear end of an arm 8 and the rear edge of the 85 lower portion 10 of each support is positioned rearwardly with respect to the lugs 5, 6. The supports 9 at the rear inner corners thereof are connected together by an integral enlargement 12 formed integral with the upper face of the base 1 and extending from one support 9 to the other. The enlargement 12 has its forward face rounded as at 13. The width of the enlargement 12 is such as not to project forwardly with respect to the lugs 90 5, 6. Each support 9 has the upper portion 11 thereof formed with a pair of spaced superposed alining openings 14, 15. The openings 14, 15 in one support aline with the openings 14, 15 in the other support and a 95 pair of alining openings is adapted to receive a pivot bolt 16 which is of a length to project from said supports 9. The head 17 of the bolt 16 abuts against the outer face of one of the supports 9 and carried on the threaded 100 end of the bolt 16 is a securing nut 18 which abuts against the outer face of the other support 9. Mounted on the bolt 16 is a pair of spacing collars 19 and one of which abuts the inner face of one support 9 and the other 105 110 of which abuts against the inner face of the other support 9.

Shiftably mounted on the bolt 16, between the collars 19, is a thrust element actuating the lever referred to generally by the reference character 20 and which consists of a straight 5 or normally vertical upper portion 21 and a rearwardly and forwardly curved lower portion 22. The lower end of the upper portion 21 of the lever 20 is formed with an opening 23 for the passage of the bolt 16. The lower 10 portion 22 has a rearwardly curved upper part 24 and a forwardly curved lower part 25 which is formed at its free or forward end with a reduced extension 26 centrally disposed with respect to said free or forward end 27. The upper part 21 of the lever 20 extends above the supports 9 and is provided with a socket 28 for the reception of a handle member 29.

The thrust element is pivotally carried by 20 the lever 20 and is coupled with the extension 26. The thrust element is constructed from a bar 28 of substantial length and which has its forward end 29 of greater height than its rear end. The forward edge of the bar 28 is serrated or toothed as indicated at 30. The rear end of the bar 28 is bifurcated as at 31 for the reception of the extension 26. The bifurcated end 13 of the bar 28 is provided with a pair of alining openings 32 and which 30 register with an opening 33 formed in the extension 26. Extending through the registering openings is a pivot bolt 34, having its head 35 abutting against one side of the bar 28, and said bolt 34 carries on its threaded 35 end a securing nut 36 which abuts against the other side of the bar 28. The thrust element is pivotally connected to the extension 26 by the bolt 34. The connecting of the thrust element with the lever 20 in the manner as stated, provides for a forward thrust movement of said element and with the travel of the latter in a longitudinal plane with respect to the upper face of the base 1. The openings 14 and 15 provide for the mounting of the bolt 16 at different heights to elevate and lower the lever 20 providing for a corresponding adjustment of the thrust element. The anchoring lugs prevent the rearward shifting of the base plate when the lever 40 45 50 55 60 65 70 75 80 85 90 95 100 105 110 115 20 is moved in the direction to shift the thrust element 28 forwardly for the purpose of alining the track.

It is thought the many advantages of a track liner, in accordance with this invention 55 owing to its extreme simplicity and obtaining a direct thrust on the track rails or the supporting means therefor can be readily understood, and although the preferred embodiment of the invention is as illustrated and 60 described, yet it is to be understood that

changes in the details of construction can be had which will fall within the scope of the invention as claimed.

What I claim is:

1. A track liner comprising a base having 65 a bifurcated forward end, opposed, spaced vertically extending supports integral with said base, a thrust element operating lever including a socketed upper part terminating in a rearwardly directed intermediate curved 70 part merging into a horizontally extending forwardly directed lower part positioned between said supports in close proximity to said base, a pivot extending through the upper ends of said supports and through the lower 75 end of said upper part for pivotally supporting said lever, spacing means mounted on said pivot between said upper part and said supports, and a forwardly directed, shiftable, thrust element free of direct connection with said base and supports and extending lengthwise of the base, said element having its rear end pivotally connected to the forward end of said lower part and said element further having its forward end of greater 80 height than its rear end, said upper part adapted to receive a handle member and further extended above said supports.

2. A track liner comprising a base having 90 a bifurcated forward end, opposed, vertically extending spaced supports integral with said base intermediate its ends, a thrust element operating lever arranged between said supports, extending thereabove and including a normally, vertically disposed socketed 95 upper part terminating in a rearwardly directed intermediate curved part merging into a horizontally extending forwardly directed lower part positioned between said supports in proximity to said base, said lower part 100 having its forward end reduced, and a forwardly directed, shiftable, thrust element free of direct connection with the base and supports arranged between the latter and extending lengthwise of the base, said element 105 positioned in close proximity to the base and having its rear end bifurcated for the reception of the reduced forward end of said lower part, means for pivotally connecting the bifurcated end of said element with the reduced end of said lower part, means for pivotally connecting the lower end of said upper part to the upper portion of said supports, and said element having the forward 110 end edge of greater height than its bifurcated end and with such forward end edge serrated.

In testimony whereof, I affix my signature hereto.

JOHN E. VARNER.
